ERNEST HOWARD FARMER, OF LONDON, ENGLAND.

METHOD AND APPARATUS FOR DEVELOPING FILM-CARTRIDGES.

1,291,453.

Specification of Letters Patent.

Patented Jan. 14, 1919.

Application filed December 29, 1917. Serial No. 209,388.

To all whom it may concern:

Be it known that I, ERNEST HOWARD FARMER, a subject of the King of Great Britain, residing at London, in the county of Middlesex, England, have invented certain new and useful Improvements in Methods and Apparatus for Developing Film-Cartridges; and I do hereby declare the following to be a full, clear, and exact description of the invention, such as will enable others skilled in the art to which it appertains to make and use the same.

My invention consists in a new and improved method of and apparatus for developing film cartridges hereinafter described, reference being had to the accompanying drawings which illustrate my improved method and to forms of apparatus for carrying the same into effect, selected by me for purposes of illustration, and my invention is fully described in the following description and claims.

My improved method and apparatus combines the advantages of both of the present methods in that while it can be performed in daylight without the use of a dark room, the film is repeatedly passed through a small quantity of developer, thereby insuring the greatest economy and the best results in the developing operation.

In its simplest form my invention contemplates the placing of the film upon a support having sufficient surface to accommodate the entire film composing the roll or cartridge to be developed, and preferably holding it in annular position, a narrow space being provided between the support for the film and the inclosing casing which protects it from the light, the developing solution, (and if desired, the fixing solution), wash waters, etc., being introduced into a portion only of this narrow space and by a relative rotation or movement between the liquid and the film support, which may be accomplished by rotating the casing and film support or otherwise, to secure the movement of the film in the small quantity of developer continuously with respect to the sensitive surface until the development is effected.

Other features of my invention contemplate special means by which the film may be introduced into and removed from the casing, and by which the developer or other liquids may be introduced into and removed

from the casing, and other details, all of which are hereinafter fully described.

Referring to the accompanying drawings:

Figure 1 represents a sectional view of an improved developing tank for carrying my invention into effect.

Fig. 2 is a transverse sectional view on line 2—2 of Fig. 1.

Fig. 3 is a detailed view of a support for the spool or roll carrying the film showing a friction device or brake attached thereto.

Fig. 4 is a similar view showing a slight modification of the friction device or brake.

Fig. 5 is a detailed view of a clip which is conveniently used for securing the film on the film support after development to facilitate the later operations.

Fig. 6 is a detailed view of a detachable film support which may be advantageously employed in carrying out my invention.

Fig. 7 illustrates a slight modification of my invention, showing the developing tank used in connection with a stationary liquid receptacle.

Fig. 8 is a sectional view similar to Fig. 1, showing a modification of my invention.

Fig. 9 is a plan view of the apparatus shown in Fig. 8 partly in section.

Fig. 10 is a partial sectional view of a slightly modified form of apparatus.

In the form of my invention shown in Figs. 1 to 6, inclusive, 1 represents the main body of my improved developing tank, which is circular in cross-section, and 2 represents the cover or closure thereof, having an annular flange 2^a to overlap a portion of the body 1, and preferably provided with an annular groove 2^b to receive the edge portion of the body 1, although this is not essential.

The body 1 is also conveniently provided with an annular bead, indicated at 1^a adjacent to the edge of the cover 2 as shown, although this is not essential. This structure is a well known box structure in common use in the manufacture of metal and other boxes, and the tank may be formed of any suitable material which will not be injuriously affected by the developing and other solutions used, or which is treated so

as not to be injuriously affected. 14 is a rubber band fitting around the junction of 1 and 2. Within this tank I provide a support for the film which is preferably attached to the revoluble cover 2 and preferably

consist of a cylindrical drum 3 perma-

nently or detachably secured to the cover 2 concentrically therewith. In Fig. 1, I have shown the cover 2 provided with a permanently attached drum 4 over which is slipped 5 a revoluble drum 3. The drum which forms the film support, in this instance the drum 3, is provided with means by which one end of the paper backing of a film roll may be secured thereto. Any suitable means may 10 be employed, and I have indicated in the drawings a pair of thin strips of metal 5—5 soldered at their ends or otherwise secured to the drum, so that the end of the paper backing may be passed under these strips 15 and folded back around one and under another in the manner indicated in Fig. 1, for example, to retain it, but I do not limit myself to this particular construction. The tank body 1 and the cover 2 are so fitted as 20 to be capable of relative rotation, and it is to be understood that the film-carrying drum may be attached either to the body 1 or to the cover 2, although I prefer to attach it to the cover 2 so that when the cover is removed 25 from the container the film support will also come with it. The part which does not carry the film support is provided with means, which while detachably supporting the film spool, prevents the accidental un- 30 winding of its paper backing and film. Any suitable means may be employed depending upon the type of spool, some of which have holes running through their central axis, others recesses only, and others again hav- 35 ing projecting trunnions. In this instance assuming the tubular type is used, a spindle 6 is located in such a position that the spool may revolve between the outside of the container and the film support. Upon this 40 spindle is carried a tube 7, Fig. 3, having at one end a flat supporting plate 8, and carrying the spool which revolves upon it.

In Fig. 3 I have shown a brake 9 of light spring brass or other suitable material 45 having angular end portions 10 provided with holes to engage the tube 7, the brake 9 being grooved inwardly so as to bear against the roll when the latter is in place, and this brake is so constructed that it will be held 50 from rotation with the spool when placed in the tank. In Fig. 3 I have shown the brake provided with projections 11 for engaging the wall of the tank 1, as shown in Fig. 2, to prevent the brake from rotating 55 with the spool. In Fig. 4 I have shown a modification of this friction brake, which consists of a roller 12 with a longitudinal aperture therethrough through which a rubber band, indicated at 13, may be passed, 60 the ends of which are placed around the tube 7 of the detachable roll support.

I will now describe the operation of the apparatus shown in Figs. 1 to 6 in carrying out my improved process. The cover 2 65 having been removed from the tank, the roll

of film is placed in engagement with the support 7—8 and the brake 9 by placing the brake over the spool and slipping the tube 7 through the spool and the apertures in the arms 10 of the brake. The end of the paper 70 backing is then secured to the retaining device 5—5 on the film supporting drum 3, it being understood that the drum 3 has a periphery at least equal to the entire length of the film to be developed. The temporary 75 support 7—8 with the spool is placed on the cover 2 and a small portion of developing solution is poured into the interior of the drum 4. The drums 3—4 do not extend to the bottom of the body 1 when the tank 80 is closed, as shown in Fig. 1, leaving a space 15 through which this developing solution can escape into the annular space between the drum 3 and the outer wall of the tank. The body 1 of the tank is then placed in engagement with the cover and at the same time the spindle 6 is passed longitudinally 85 through the tube 7 of the detachable roll support, thereby securing the roll to one part of the tank (in this instance the body 90 1), while the end of the paper backing is secured to the other (in this instance the drum 3), carried by the cover 2. The operator will then effect a relative rotation between the body 1 of the tank and the cover 95 2, as indicated by the arrow in Fig. 2. This causes the roll of film indicated at 16 to be moved around the film support 3, thereby unrolling the paper strip and film and winding the same around the support 3, as 100 will be readily understood. Fig. 2 also shows the manner in which the brake 9 is prevented from rotating with the spool. This movement is continued until the film is entirely unrolled, which can be determined by suitable registering marks on the exterior of the tank and cover. Obviously, 105 the relative rotation would be more than a complete rotation in order to carry the spool over the first portion of the black 110 paper backing and apply the entire length of the film around the film support 3, indicated in Fig. 2. When this has been done the entire surface of the film will be supported within the annular space between 115 the film support or drum 3 and the annular wall of the tank, one end of the black paper being held by the retaining device 5 and the other end being held on the spool. The rubber band is finally pulled over the 120 junction. The tank is now moved to such a position that the developing solution within the drum 4 can pass out through the space 15 into the annular space which is indicated at 17. Only a sufficient quantity of 125 this developing solution is used to insure the wetting of a portion of the film when the tank is set on edge, as indicated in Fig. 2, in which the solution is indicated at 18. The operator will now effect a relative rota- 130

tion between the film support and the developing solution. As the liquid tends to remain always at the lowest point, this can be very readily and conveniently effected in the use of the apparatus shown in Figs. 1 to 6 by simply rolling the entire tank backward and forward on a table or other flat surface, or round and round in a basin, thus bringing every portion of the film in contact with fresh portions of the developing solution and the period of development can be readily determined by timing the same.

It will be seen that this operation can be carried out in daylight without the use of a dark room, and even in the field, it being only necessary to have the developing solution and water for washing purposes. As soon as the development is completed, the cover 2 may be removed sufficiently to let the developer run out, when the fixing solution may be poured in and the film "fixed" in the same manner. After the film has been developed the parts of the tank can be separated and the roll disengaged from the spindle 6. The portion of the black paper backing adjacent to the roll can be cut off and attached to the film support by means of a suitable clip, such for example as shown in Fig. 5 and indicated by the numeral 19, and the cover 2 carrying the film support can be placed in a vessel containing water for washing the film, after which the film can be dried while still remaining on the film support, or it can be removed and hung up if desired. In some instances I may use the drum 4 as the film support and attach the retaining devices 5—5 thereto, dispensing with the revoluble drum 3. Where the revoluble drum 3 is employed, as soon as the development of film is completed and the tank opened, the drum 3 can be removed after attaching the free end of the film thereto by means of the clip 19, and the washing and drying operations can be carried out while the film is on the detachable drum 3. By providing the tank with a number of drums 3, the development of other films can proceed in the tank while those developed are being fixed and dried on the detachable drums 3. The fixing operation can be carried out in the tank as before described or in a separate receptacle after the removal of the film on its support, as preferred.

In Fig. 7 I have shown a slight modification of the apparatus shown in Figs. 1 to 6, inclusive, in which the tank here indicated at 1^a is provided with an aperture 20 for the admission and exit of liquid, suitable flanges or partitions 21—22 being provided on the inside of the tank to prevent light from entering through the aperture 20. In other respects the tank and its cover is constructed exactly as heretofore described, the rubber

band being omitted. Where the tank is thus provided with an inlet aperture it is unnecessary to insert the developer before closing the tank. A portion of the tank containing the aperture may be immersed in a liquid-containing tray having substantially the same shape as the inclosed portion of the tank, in which case the solution will pass up through the aperture 20 when at the lowest position, as shown in Fig. 7, and may be brought into engagement with all parts of the film by rotating the tank in the tray which is indicated at 23, a very small quantity of developing solution being required in such case, as will be apparent. In using this form of the apparatus, the developing solution can be drawn out through the aperture 20, and the fixing solution and water for washing, or any other solutions, can be introduced and applied to the film in the same manner.

While the relative rotation to remove the film from the cartridge and position it on the developing support can probably be most economically and conveniently effected in the smaller sizes by simply revolving the two parts of the outer container, it may be effected in other ways. For example, in some instances the film supporting drum can be made rotatable with respect to the tank, in which case it is not necessary that the tank should be rotated to position the film. In Figs. 8 and 9 I have shown such a construction. In these figures the tank is indicated at 101 and the cover therefor at 102. On the inner face of the cover I have shown a revoluble disk 125, having an axial portion extending through the cover and provided with a squared portion at 126 engaged by a suitable handle 127, which in this instance is a flat plate having a central opening fitting over the squared portion 126 and held in place by a retaining screw 128 provided with an enlarged head, which construction prevents light from entering the interior. The disk 125 is provided with means for supporting the film, and I prefer to employ a detachable film support, indicated at 103, frictionally engaging an annular flange 104, carried by the disk 125. I may provide the disk, in some instances, as shown in Figs. 8 and 9, with a plurality of these supporting flanges 104, four being shown herein of different diameters, to receive film supporting drums 103 of different diameters. This provides for supporting films of different lengths for developing and also adapts the device for another purpose. For example, after a considerable number of films have been developed and dried as in the field or elsewhere, a large number of films may be rolled upon the film supporting drum or drums 103 and the drums can then be applied to the supporting flanges 104 one within the other, so that the drums 130

can be used as a storage or carrying case, transporting films or retaining them and protecting them from injury. I also prefer to provide the disk 125 with a centrally located drum 129. The developing tank will be provided with means for supporting the film roll independently of the rotatable disk 125, which may be the spindle 6, tubular support 7—8 and friction device heretofore described with reference to Figs. 1 to 6, inclusive, if the spools on which the films are carried are provided with a longitudinal hole. It will be understood that my invention is adapted equally well to the development of films carried on other spools such as those which have projecting trunnions, it being only necessary to modify the spool supporting means to meet the requirements of such spools, and in Figs. 8 and 9 I have shown one form of apparatus which may be conveniently used to support spools provided with projecting trunnions, one of which is indicated at 116. In this instance the cover 102 is provided with a spool support in the form of the segment of a cylinder indicated at 107 having a bottom plate 108 provided with an aperture to receive one of the trunnions of the spool, and a top plate carrying a spring 108^a which is provided with an aperture to receive the other trunnion so that the spool may be placed in position by simply pressing it into the shell or holder 107. The shell 107 is conveniently provided with a friction spring, indicated at 109 in Fig. 9, to bear against the spool and act as a brake to prevent the film and paper from accidentally unwinding. The film support 103 is provided with means for retaining one end of the paper backing, as for example, the strips 5—5 shown in Fig. 6, and one end of the backing will be attached to the film support in this manner, the roll being placed in the roll support 107. The developer may be introduced into the tank in the manner described with reference to Figs. 1 and 2 by putting it within the drum 129 before closing the tank, or it may be inserted after the tank is closed, as preferred. In Fig. 8, for example, I have shown two means by which the developer or other liquid may be introduced into the tank, either one or both of which may be employed. 130 represents a tubular part extending from an aperture in the bottom of the tank 101 normally closed by screwing plug 131. By unscrewing this plug, developing or other solution or water can be introduced into the interior of the tank after the same is closed. I have also shown an aperture in the cover adjacent to the roll support, closed by a plug 132 and communicating with the interior of the tank in such manner as to prevent light from entering, if the aperture is intended to be used as an inlet for developer, although this is

not necessary in case it is used only for an exit aperture. By unscrewing the plug 132 developer or other liquid may be poured out or a liquid inserted if the aperture is protected as above noted. I prefer to provide 70 the tank with both plugs 131 and 132.

In the use of the apparatus shown in Figs. 8 and 9, the film is wound from the spool around the film support 103 by rotating the disk 125 by means of the handle 127 75 on the outside of the cover. The development will be effected by rocking or rotating the tank in the manner previously described.

It will be seen that in the use of the various forms of apparatus which I have described, for carrying out my improved method, the fresh parts of the developer are continually brought into contact with the surface of the film, which is held face downward with respect to the developer, at the 80 time of contact therewith, so that the motion of the developer with respect to the film prevents the adherence of bubbles or dust particles or grit, and there is no frictional contact between the sensitive surface under 90 treatment and any part of the tank, so that no injury to the sensitive surface can result.

It will easily be understood that while a very small quantity of developer can be used by effecting the relative rotation between the developer and the film, my improved apparatus can also be employed in connection with sufficient quantities of developer to entirely fill the tank, in which case the tank may be used horizontally without rotating it. This has the disadvantage of requiring a large quantity of developer, which, however, can be partially avoided, if the apparatus is to be used in this manner, by providing a displacement member within 105 the film-supporting drum. For example, by closing the supporting drum 4 of Fig. 1 at the end nearest the bottom of the tank and thereby displacing the quantity of developer within which would be required to fill the 110 central portion of the tank and confining it to the annular space outside of the film-holding drum.

In Fig. 10 I have shown a slightly modified form of the invention in which the film spool and liquid-admitting light trap are located adjacent to an aperture in the side wall of the container, access to which is obtained through this aperture for the insertion and removal of the spool or roll, the 115 said aperture being provided with a cover which preferably contains the liquid-admitting aperture and its light trap. In this figure, 201 represents the container provided on the interior with the rotatable film-supporting drum 203, similar to that shown in Figs. 8 and 9 and capable of being rotated by suitable handle on the outside of container as shown in those figures. The container 201 is provided in its side wall with a 120

flanged aperture, the flanges being indicated at 225. The lateral opposed flanges are provided with bearings 226 for receiving and retaining the spool-supporting spindle 207 and brake indicated at 212, which is, as shown, of the form indicated in Fig. 4. 227 is a cap fitting the flanged portion 225 and provided with an aperture 220 for the admission of liquid into the interior, in case the tank is to be supplied with the fluid by immersing it in a liquid, in which case the light traps 221—222 are arranged adjacent to the aperture 220. If the liquid is to be poured into the container before closing the cover 227, the aperture 220 and its light traps can be omitted.

What I claim and desire to secure by Letters Patent is:

1. The herein described method of treating roll films which consists in supporting the film in substantially annular form around a horizontal axis within a light-tight container, with its sensitive surface disposed outwardly in conjunction with a small body of liquid at the lowest portion of the container sufficient to contact with a portion only of the sensitive surface, and rotating the container about said horizontal axis, to bring successive portions of the sensitive surface into contact with said liquid.

2. The herein described method of treating roll films which consists in supporting the film in wound condition within a light tight container, effecting the unwinding of the film within the container and supporting the entire film face outward in substantially annular position, introducing a small quantity of liquid within the container from below, by means of a light proof aperture, sufficient to contact with the sensitive face of the film at the lowest part of the container and rotating the container to bring portions of the liquid into contact with all portions of the film.

3. In a developing apparatus for roll films, the combination with a container, comprising separable members rotatable one with respect to the other, a substantially annular film support separate from said members, located within said container, and detachably secured to one of said members, means on the other side of said members for supporting a film roll, and means on said film support for securing the film thereto, whereby said film support can be removed from engagement with the member to which

it is detachably secured without removing the film therefrom, to permit further treatment of the film and further use of the developing apparatus with another film support.

4. In a developing apparatus for roll films, the combination with a container, comprising separable and relatively rotatable members, of a film supporting drum within said container and carried by one of said members, a film roll supporting spindle within said container carried by the other member, located exteriorly with respect to said drum, and a retaining device on said drum. 70

5. In a developing apparatus for roll films, the combination with a container comprising separable and relatively rotatable members, of a film-supporting drum within said container, carried by one of said members, 75 a spindle within said container, carried by the other member and located exteriorly with respect to the drum, a detachable roll support having a tubular portion for engaging said spindle, and a retaining device 80 on said drum.

6. In a developing apparatus for roll films, the combination with a container comprising separable and relatively rotatable members, of a film supporting drum within 85 said container, carried by one of said members, a spindle within said container, carried by the other member and located exteriorly with respect to the drum, a detachable roll support having a tubular portion for engaging 90 said spindle, a friction brake carried by said roll support, a retaining device on said drum.

7. In a developing apparatus for roll films, the combination with a container comprising separable, relatively rotatable members, of a film-supporting drum within said container, carried by one of said members, a roll support within said container, carried by the other member and located exteriorly 100 with respect to said drum, a retaining device on said drum, said container being provided with means for introducing and discharging a liquid without separating said separable members, and a liquid-containing 105 vessel separate from said container and having its bottom and sides conforming to and of a size sufficient to inclose a portion of said container.

In testimony whereof I affix my signature. 110

ERNEST HOWARD FARMER.
